UNITED STATES PATENT OFFICE

139,906

DESIGN FOR A CHILD'S DRESS

Etta Evans, New York, N. Y.

Application October 26, 1944, Serial No. 115,985

Term of patent 14 years

(Cl. D3—26)

To all whom it may concern:

Be it known that I, Etta Evans, a citizen of the United States of America, residing in New York city, county of New York, and State of New York, have invented a new, original, and ornamental Design for a Child's Dress, of which the following is a specification, reference being had to the accompanying drawing, forming part thereof, wherein,

I claim:

The ornamental design for a child's dress, substantially as shown.

ETTA EVANS.
